US00D576477S

(12) **United States Design Patent**
Levy

(10) **Patent No.:** **US D576,477 S**
(45) **Date of Patent:** **** Sep. 9, 2008**

(54) **HIGH PRESSURE ENERGIZABLE TUBE CONNECTOR**

(75) Inventor: **David Levy**, Broussard, LA (US)

(73) Assignee: **Petrotechnologies, Inc.**, Broussard, LA (US)

(**) Term: **14 Years**

(21) Appl. No.: **29/281,379**

(22) Filed: **Jun. 21, 2007**

(51) LOC (8) Cl. **08-08**

(52) U.S. Cl. **D8/382**; D23/262

(58) Field of Classification Search **D8/382; D23/262; 285/342**
See application file for complete search history.

(57) **CLAIM**

The ornamental design for a high pressure energizable tube connector, as shown and described.

DESCRIPTION

FIG. 1 depicts a perspective view of a high pressure energizable tube connector;

FIG. 2 depicts an elevated top view thereof;

FIG. 3 depicts an elevated right side view thereof;

FIG. 4 depicts an elevated left side view thereof;

FIG. 5 depicts an elevated front view thereof; and,

FIG. 6 depicts a cross sectional view along the central axis of FIG. 2.

1 Claim, 3 Drawing Sheets

FIG. 1
